UNITED STATES PATENT OFFICE.

WILLIAM F. M. GOSS, OF URBANA, ILLINOIS.

LOCOMOTIVE-ENGINE.

1,275,672.

Specification of Letters Patent. Patented Aug. 13, 1918.

Application filed May 21, 1916. Serial No. 235,772

To all whom it may concern:

Be it known that I, WILLIAM F. M. Goss, of Urbana, in the county of Champaign and State of Illinois, have invented a certain 5 new and useful Improvement in Locomotive-Engines, of which improvement the following is a specification.

My invention, while particularly designed for application in locomotives operating in 10 service at railroad terminals, which are generally of the type known as "yard" or "switching" engines, is equally and desirably applicable in locomotives used in general road service.

15 The growth of cities and the increase of railroad traffic incident to their development and maintenance, has, in recent years, emphasized the objectionable results of the operation of steam locomotives, which consist in the discharge of smoke and dirt (particles of fuel and ash) from the stack, and the noise made by the exhaust blast. To overcome these objections, demands have arisen, in many localities, for the complete 20 elimination of steam locomotives from terminal traffic, and the substitution of electric propulsion therefor, which radical change, has, by reason of its high cost of installation and maintenance, thus far 25 proved too expensive to be generally accepted as a means of removing the objections above noted. Consequently, the residents of cities continue to suffer the annoyance of smoke, dirt, and noise, which is now inseparably associated with steam locomotive 30 operation.

The object of my invention is to provide a draft appliance, adaptable to application, without interference with existing accessories, in locomotive boilers of the present 35 standard construction, in the operation of which appliance there shall be attained the substantial advantages of: (a), reducing by a more effective utilization of the draft inducing capacity of the exhaust steam, the back pressure in the locomotive cylinders, and correspondingly increasing the efficiency of the propulsive action of the steam on the pistons thereof; (b), reducing the amount 45 of visible smoke emitted, by a more perfect control of the draft action; (c), separating solid matter from the smoke, and preventing its discharge from the stack, whereby the percentage of dirt which is normally emitted 50 is materially reduced; (d), economization of

fuel by the utilization of solid material which, in ordinary operation, is wasted; (e), effecting the entire suppression of the noise of the exhaust; (f), insuring more effective blower action, when the locomotive is standing or drifting, and suppressing the noise of the ordinary blower, and; (g), providing for the ready and expeditious removal and replacement of the apparatus, as may, from time to time, become necessary or desirable 60 for renewal or repair of its own members or of other accessories of the locomotive boiler.

The improvement claimed is hereinafter fully set forth.

In the accompanying drawings: Figure 1 70 is a vertical longitudinal central section through the forward portion of a locomotive boiler of standard type, illustrating an application of my invention; Fig. 2, a vertical transverse section through the smoke box, on the line $x-x$ of Fig. 1; Fig. 3, a vertical longitudinal central section through the exhaust connection, turbine casing, turbo-muffler, and draft fan; Figs. 4 and 5, vertical transverse sections, on the lines, $y-y$ and $z-z$, respectively, of Fig. 3; Fig. 6, a rear view, in elevation, of the draft fan; Fig. 7, a front view of the turbine casing, and; Fig. 8, a partial section through the fan housing, illustrating the addition of a spark arresting netting. 80

Referring descriptively to the specific embodiment of my invention which is herein exemplified, it is illustrated as applied in a locomotive boiler of the present standard type, in which the shell or waist, 1, is traversed by a plurality of fire tubes, 2, which extend from a firebox at the rear, which is not shown, to a smoke box, 4, connected, in the usual manner, to the shell, 1, of the boiler. The forward end of the smoke box 95 is closed by a front, 4^a, having a door, 4^b, closing an opening in the front through which access is afforded to the interior of the smoke box, for the insertion and removal of members contained therein, and in the forward portion of the shell, is a superheater header, 5, superheater pipes, 5^a, steam pipe, 6, etc. The smoke box is supported on cylinder saddles, 7, in the usual manner, and is provided at top, with the usual passage, 105 open to the stack, 8, through which the waste gases of combustion are discharged to the atmosphere.

In the practice of my invention, as applied in a locomotive boiler of the type 110

above described, the ordinary vertical exhaust pipe, and exhaust tip or nozzle, are substituted by a turbine casing, and a connected "turbo-muffler," the construction of which, and their relation to the locomotive cylinders and boiler will now be described. The turbine casing, 9, is an annular casting, located substantially concentric with the cylindrical wall of the smoke box, the rear end of which casting is flanged, and is connected by bolts to the flanged front of a hollow turbo-muffler, 10, which is preferably made in two sections, bolted together in its horizontal axial plane, and is in the form of a frustum of a cone, having its smaller end, which is at its rear, slightly beveled or flared outwardly, as most clearly shown in Fig. 3. Lateral downwardly projecting legs, 10^a, are formed on the turbo-muffler, and are connected, detachably, as by bolts and nuts, to vertical standards, 10^b, extending longitudinally in the smoke box and secured to the cylinder saddles, 7. The smoke box door opening is made of sufficiently large diameter to enable the turbine casing and connected turbo-muffler to be passed through it, for insertion in, and removal from, operative position as desired.

36 An exhaust supply passage, 9^a, which is open at its lower end, is bolted to the front of the turbine casing, 9, the lower end of said passage being connected to a short curved exhaust connection elbow, 7^a, which communicates, in the manner of an ordinary exhaust pipe, with the exhaust passages of the cylinder saddles. An exhaust discharge plate, 10^c, is fixed to the rear end of the turbo-muffler, being preferably, as shown, 40 cast integral therewith and connected thereto by ribs, 10^d, at such a distance therefrom as to provide a space which is open to an annular discharge passage interposed between the shell of the turbo-muffler and a flange, 10^e, projecting from the adjacent side of the discharge plate, and curved in conformity with the end of the turbo-muffler, as shown in Figs. 3 and 5.

50 An operating shaft, 12, is journaled in bearings, 10^f, 10^g, in the turbo-muffler, 10, and a steam turbine, 13, which may be of any suitable known and preferred construction, is fixed on the forward end of said shaft. A draft fan, 14, is fixed on the rear end of the operating shaft, and a thrust bearing, 10^g, is supported on the turbo-muffler, between the journal bearings, 10^f, 10^g. The journal and thrust bearings are enclosed in a recess formed in a central supporting standard, 10^h, cast integral with or secured to, the turbo-muffler, and covered by a cap 10ⁱ, an oil receptacle being thereby formed, to which lubricating material may be supplied through a pipe, 19, leading from a source of supply exterior to the

boiler. A suitable drainage port, 10^k, (one or more) is formed at the larger end of the turbo-muffler.

Exhaust steam is supplied to the buckets of the turbine, 13, when the locomotive is running with open throttle, from the connection elbow, 7^a, and supply passage, 9^a, through a plurality of ports, 13^a, formed in the rear wall of the passage, 9^a, and disposed in a circle concentric with the operating shaft. For the purpose of operating the turbine when it is desired to increase the draft in periods in which the locomotive is standing or dripping, a valve controlled blower pipe, 15, is led from the steam space 80 of the boiler into the turbine casing, 9, said pipe being open to the buckets of the turbine through supplemental ports, 13^b, in the rear wall of the passage, 9^a.

The portions of the smoke box, 4, in front and in rear, respectively, of the draft fan, 14, are separated by a partition or fan housing, 16, which closely surrounds the rear end of the draft fan, and is open centrally thereto. The fan housing is forwardly curved or inclined, and at its forward end, is inwardly recurved, as shown in Fig. 1, its inwardly curved portion forming a baffle and constituting the wall of an annular peripheral chamber, 16^a, into which dust or solid matter, discharged from the boiler tubes, is driven by the centrifugal force generated by the revolutions of the draft fan. As will be readily understood, the space within the smoke box, in front of the fan housing, 16, will, when the locomotive is in operation, always be subject to pressure greater than that of the atmosphere and the space in rear of said housing, to pressure less than that of the atmosphere, 105 the difference in pressure being due to the action of the draft fan. A delivery nozzle, 16^b, projects from the lower portion of the chamber, 16, through the shell of the smoke box, and a delivery pipe, 17, leads from said nozzle to any preferred receptacle, which may be the firebox of the boiler, the ash pan, or a box or casing from which the delivered solid matter may be withdrawn from time to time as may be required.

110 The space between the chamber, 16, and the turbo blower, which is open to that forward of it in the smoke box, may, if rendered desirable by exceptional conditions, or required by legal enactment, be closed by a sheet of netting or perforated plate, 18, as indicated in Fig. 8.

115 In the operation of the appliance, when the locomotive is running under steam, *i. e.* 120 with its throttle open, all the exhaust steam from the cylinders is delivered to the turbine, 13, which, with the connected draft fan, 14, is thereby rotated. The centrifugal action of the wings of the fan, upon the 130

products of combustion passing out of the tubes of the boiler, draws the gaseous and solid matters of the products to and through the central opening of the partition, 16, and into the circumferential chamber, 16^a, thereof. The gaseous constituents are forced by the fan through the annular space between the wall of the chamber and the turbo-muffler, into the smoke box space 10 which is forward of the housing, from which they are continuously discharged to the atmosphere. The dust and solid matter contained in the products of combustion drop to the bottom of the chamber, 16^a, 15 from which they are also continuously discharged through the nozzle, 16^b, and delivery pipe, 17. The exhaust steam from the turbine fills the space within the turbo-muffler, 10, and thence escapes, in a quiet 20 continuous outflow stream through the annular discharge passage between the turbo-muffler and the flange, 10^c, of the end plate, 10^c, to the smoke box, and therefrom to the atmosphere, through the stack. If the condition 25 of the fire should be such as to require artificial draft when there is no exhaust from the locomotive, which is the case when standing or drifting, the turbine and draft fan are started, at greater or less 30 speed as required, by the admission of boiler steam to the turbine through the blower pipe, 15.

Among the operative advantages, the following may be noted. The exhausting action 35 of the draft fan upon the products of combustion, causes the actual value of the negative and positive pressures in the smoke box, as measured from atmospheric pressure, to be less than in ordinary practice. Thus, the reduction of pressure in the space 40 in rear of the fan housing need be only sufficient to draw the products of combustion through the boiler tubes and the central opening of the fan housing, and the 45 excess of pressure in the space forward of the fan housing need only be sufficient to discharge the intermingled gaseous products of combustion and exhaust steam through the stack, at sufficient velocity to 50 carry the issuing column clear of the locomotive. As a result of this arrangement, the problem of maintaining the smoke-box against leakage, as compared with present practice, is simplified. The steam turbine 55 and fan constitute a more efficient device for utilizing the energy of the exhaust steam in creating draft than the exhaust pipe and tip common in present practice, and from this fact there results a reduction of back 60 pressure in the locomotive cylinders and a corresponding economy as compared with the present practice. Another material feature of advantage is found in the complete elimination of the harsh noise of the ordinary exhaust and of the ordinary blower,

and the minimization of liability to the discharge of smoke, and especially of solid matter, to the atmosphere, with the capacity of the utilization of the unconsumed particles of fuel by their return to the fire-box. 70 Again, the operating shaft and its bearings being, when operating, inclosed in exhaust steam, they are protected from deterioration by the action of the high temperature of the front and gases. The capacity of 75 ready removal and replacement of the turbo-muffler and its attachments is also a feature of much practical value, as upon detaching the connections with the exhaust connection and supports, which can be readily and quickly done, the turbo-muffler and related parts can be slid, upon the supports, out of the smoke box, thus affording ready access to the superheater and front tube sheet whenever required. 80 85

I claim as my invention and desire to secure by Letters Patent:

1. The combination, with a locomotive boiler, of means, located in the smoke box thereof, for exhausting products of combustion from the boiler tubes; means for conducting the exhaust steam from the cylinder exhaust passages of the locomotive to

said exhausting means; and a partition in the smoke box, having a passage through 95 which the products of combustion are drawn by the exhausting means, in their traverse to an atmospheric discharge passage.

2. The combination, with a locomotive boiler, of means, located in the smoke box 100 thereof, for exhausting products of combustion from the boiler tubes; means for conducting the exhaust steam from the cylinder exhaust passages of the locomotive to said exhausting means; a partition in the smoke 105 box, having a passage through which the products of combustion are drawn by the exhausting means, in their traverse to an atmospheric discharge passage; and a peripheral chamber at the front of said partition, communicating with the passage thereof. 110

3. The combination, with a locomotive boiler, of means, located in the smoke box thereof, for exhausting products of combustion from the boiler tubes; supports, fixed in the smoke box, to which said exhausting means are detachably connected; a door controlled opening in the smoke box front, of diameter sufficient to permit the insertion 115 and removal of the exhausting means in and from the smoke box; and a detachable connection from the cylinder exhaust passages of the locomotive to the exhausting means. 120

4. The combination, with a locomotive 125 boiler, of means, located in the smoke box thereof, for exhausting products of combustion from the boiler tubes; means for conducting the exhaust steam from the cylinder exhaust passages of the locomotive to 130

- 1 said exhausting means; a partition in the smoke box, having a passage through which the products of combustion are drawn by the exhausting means, in their traverse to an atmospheric discharge passage; a peripheral chamber at the front of said partition, communicating with the passage thereof; and a delivery passage leading out of said chamber.
- 10 5. The combination, with a locomotive boiler, of means, located in the smoke box thereof, for exhausting products of combustion from the boiler tubes; means for conducting the exhaust steam from the cylinder exhaust passages of the locomotive to said exhausting means; a partition in the smoke box, having a passage through which the products of combustion are drawn by the exhausting means, in their traverse to an atmospheric discharge passage; and a valve controlled conduit for supplying steam from the boiler to the exhausting means.
- 15 6. The combination, with a locomotive boiler, of a casing or hollow turbo-muffler, supported in the smoke box thereof, an operating shaft, journaled in said casing; a turbine casing fixed to one end of the turbo muffler; a steam turbine fixed on one end of the operating shaft and rotatable in the turbine casing; a draft fan fixed on the opposite end of the operating shaft; means for conveying exhaust steam from the cylinder exhaust passages of the locomotive to the turbine casing; and an exhaust passage at the end of the turbo-muffler farther from the steam turbine.
- 20 7. The combination, with a locomotive boiler, of a casing or hollow turbo-muffler, which is open at its ends and is supported in the smoke box of the boiler; an operating shaft journaled in said casing; a turbine casing fixed to one end of the turbo muffler; a steam turbine fixed on one end of the operating shaft and rotatable in the turbine casing; a draft fan fixed on the opposite end of the operating shaft; means for conveying exhaust steam from the cylinder exhaust passages of the locomotive to the turbine casing; and an exhaust discharge plate fixed to the turbo-muffler between the draft fan and its adjoining open end.
- 25 8. The combination, with a locomotive boiler, of a casing or hollow turbo-muffler, which is open at its ends and is supported in the smoke box of the boiler; an operating shaft journaled in said casing; a turbine casing fixed to one end of the turbo-muffler; a steam turbine fixed on one end of the operating shaft and rotatable in the turbine casing; a draft fan fixed on the opposite end of the operating shaft; means for conveying exhaust steam from the cylinder exhaust passages of the locomotive to the turbine casing; and an exhaust discharge plate fixed to the turbo-muffler between the draft fan and its adjoining open end.
- 30 9. The combination, with a locomotive boiler, of a casing or hollow turbo-muffler, supported in the smoke box of the boiler; an operating shaft journaled in the smoke box; an annular flange projecting from the operating shaft and encircling the adjoining end of the turbo-muffler but spaced away therefrom.
- 35 10. The combination, with a locomotive boiler, of a casing or hollow turbo-muffler, supported in the smoke box of the boiler; an operating shaft journaled in the smoke box; an annular flange projecting from the operating shaft and encircling the adjoining end of the turbo-muffler but spaced away therefrom.
- 40 11. The combination, with a locomotive boiler, of two longitudinally extending standards fixed in the smoke box thereof; a casing or hollow turbo-muffler, having downwardly projecting legs, connected detachably to said standards, an operating shaft journaled in said casing; a turbine casing fixed to one end of the turbo-muffler; a steam turbine fixed on one end of the operating shaft and rotatable in the turbine casing; a draft fan fixed on the opposite end of the operating shaft; an exhaust connection elbow, communicating with the cylinder exhaust passages of the locomotive; an exhaust supply passage casting attached to the turbine casing and connected detachably to said elbow; and a smoke box front, having a door controlled opening of diameter sufficient to permit the passage through it of the turbo muffler and connected members.
- 45 12. The combination, with a locomotive boiler, of a partition extending across the smoke box thereof, between the front tube sheet and the stack, and having a through passage; means, located in the smoke box, forward of said partition for exhausting products of combustion from the boiler tubes through said passage; means for conducting the exhaust steam from the cylinders of the locomotive to said exhausting means; and means for discharging said exhaust steam into the smoke box, forward of said partition.
